UNITED STATES PATENT OFFICE.

HARVEY GILES, OF BROOKLYN, NEW YORK, ASSIGNOR TO ARTEMAS WARD INC., A CORPORATION OF DELAWARE.

COIN-CONTROLLED VENDING MACHINE.

Application filed July 21, 1926. Serial No. 123,827.

This invention relates to improvements in coin-controlled vending machines.

My invention resides in the novel features, structure and combination of parts herein-
5 after described and more particularly pointed out in the claims.

One of the objects of this invention is to improve and facilitate the operation of the merchandise ejecting mechanism coin-con-
10 trolled vending machines of the general type shown and described in my former Patent No. 1,476,361 by effectively excluding and clearing away from the parts cooperating with the coin carriage all extraneous matter
15 which might obstruct the path of the coin-carriage and coins carried thereby and also aiding in the discharge of the pieces of merchandise, and comprises the use of a hinged member movable with the coin carriage and
20 arranged in the initial position of said coin-carriage to extend from the carrier to a portion of a cooperating platform to exclude extraneous matter from the working parts
25 of the carriage mechanism and then during the movement of the carriage to contact with and closely hug the surface of said co-
30 operating platform to sweep and clear the coin-lifting and coin-slotted portions of said platform, and coin-discharge slots beneath the merchandise tray, and thereafter to assume a position which will effectively guide the piece of merchandise and facilitate the discharge thereof.

With these and other objects in view, the coin-controlled mechanism of my invention comprises the combination of members and arrangement of parts so combined as to co-
35 act and cooperate with each other in the performance of the functions and the accomplishment of the results herein contemplated, and comprises in one of its adaptations the species or preferred form illustrated in the accompanying drawings, in which:—

Fig. 1 is a vertical section, partly broken away through the lower portion of the machine, taken on the dotted line 1—1 of Fig. 3 and showing all the parts of the mechanism in their normal inoperated position but with a coin shown as having been fed to the machine and become arrested in position for use in ejecting the bottom piece of confection from the compartment of the tray in line with it on the subsequent operation of the machine by an outward pull on the ex-
55 posed end of the operating rod or handle;

Fig. 2 is a section corresponding with Fig. 1 but illustrating the mechanism as having been completely operated by the outward pull of the operating rod or handle, the ejected piece of confection being indicated by dotted lines and the coin being similarly indicated as having been released and descending to the coin-box;

Fig. 3 is a horizontal section through the machine, taken on the dotted line 3—3 of Fig. 1, the mechanism being shown in its normal inoperated position;

Fig. 4 is a sectional view corresponding with Fig. 3 but showing the mechanism as having been operated by an outward pull of the operating rod or handle;

Fig. 5 is a top view of the horizontal frame portion of the carrier showing my sweeping and guiding plate hinged thereon;

Fig. 6 is a perspective view of the combined sweeping and guiding plate removed from the carrier.

In the drawings, 30 designates the exterior casing of the machine as a whole, said casing comprising a back 31, sides 32, a lower front door or section 35, and a removable front or door 36. In the rear of the door 36 is formed a chamber for a tray, numbered as a whole 37, for holding the stacks or vertical columns of confections, and within the lower portion of the casing is formed a chamber for the operative mechanism of the machine and also for a coin receptacle 38 which receives the coins after they have left the operative mechanism and from which coins may be removed, when desired.

At the rear of the coin-box or receptacle 38 is provided a chute 41 down which the pieces of confection dislodged by the operative mechanism from the tray will be caused to slide to an opening below the front section 35 of the casing and from which opening said pieces may be removed by hand.

The lower front section 35 has a recess 43 therein for the fingers of the operator and a slot 44 through which the operating rod or handle 45 may be moved forwardly and rearwardly.

The upper portion of the front section 35 is formed with coin entrance slots 59.

The tray 37 has a back partially removed at its lower end as at 37' to provide a discharge opening for pieces of confectionery

and sides, as usual, and also front laterally extending flanges 60 to aid in retaining the stacks of pieces of confection, numbered 61, in position. In the present instance the tray 37 contains six vertical compartments.

At the lower front portion of the tray 37 and secured thereto, is a plate 27 having coin-entrance openings 26 in line with the bottoms of the tray-compartments and lower edge members extending rearwardly therefrom below the tray partitions and forming the supporting flanges 69.

Upon the stacks of confection 61, I place weights 77 which serve to press the pieces of confection downwardly.

That portion of the machine which may be designated as the operative mechanism and which is located above the coin receptacle 38 and partly below the upper inwardly turned portion of the lower front door 35 and partly below the main tray 37, may be handled as a unit, and this mechanism comprises a stationary main supporting frame numbered as a whole 79, a slideable frame or carriage 80 mounted thereon, a pair of levers 81 loosely connected at their outer ends with said frame or carriage 80 and at their inner ends having a pivotal bearing connection with the main operating rod or handle 45, a hinged coin-plate 83 hung from its upper end from the upper forward portion of the main frame 79. The carriage 80 is equipped with means, hereinafter described, for supporting and carrying the coins against the pieces of confection at the bottom of the tray 37, and said carriage 80 has a direct rearward and forward movement, the movement toward the rear and toward the lower end of the tray 37 being caused by an outward pull on the operating rod or handle 45 and the return movement toward the front of said carriage being caused by two coiled springs 84 whose forward ends are connected to the levers 81, and whose rear ends are connected to a stationary member of the main frame 79.

The main frame 79 comprises two corresponding vertical side plates 85 which are connected together at their lower front ends by a plate or bar 86 through which the operating rod or handle 45 passes. The plate or bar 86 has two rearwardly extending right angle bracket plates 87 upon which the levers 81 are pivotally mounted. The bar 86 also has secured to it a supporting plate 88 which extends rearwardly, and is secured to a plate member 94 depending from and formed in a single piece with a platform 104, and having a horizontally-extending struck-up flange 94' on which is supported a U-shaped channel 89 forming a guiding member and stop for the rear end of the operating rod 45. The body of the operating rod or handle 45 slides on the plate 88 and when said rod or handle is returned in-

wardly or toward the rear by the springs 84, the rear end thereof engages said stop 89 which arrests said rod or handle in its predetermined position for subsequent operation. The inner end of the rod or handle 45 has a depending pin 90 which guides within a slot 91 formed in the plate 88 and said pin and slot limit the outward movement of said rod or handle.

The rod or handle 45 has secured on it a pin 92 against which depending arms of the levers 81 are constantly pressed by means of the springs 84. The depending arms of the levers 81 thus have a constant bearing against the pin 92 which is rigid with a rod or handle 45 and will be pulled outwardly when said rod is pulled outwardly, as shown in Fig. 3, and be retracted inwardly and move the rod 45 inwardly when said rod is released and the springs 84 are permitted to operate through the levers 81 to retract said rod.

Secured to the rod 45 is an upwardly extending and rearwardly deflected broad leaf spring 99 which is rigid with the rod or handle, and at its upper end, when said rod is at its inner position, engages the lower portion of the hinged coin-plate 83, as shown in Fig. 1, and serves to retain said coin-plate in its operative position for guiding coins from the coin entrance slots to the means mounted on the carriage 80 for receiving said coins. When the operating rod or handle 45 is pulled forwardly, it carries the leaf spring 99 from engagement with the hinged plate 83 and at that time said plate will turn downwardly by gravity, as shown in Fig. 2, and release any paper or the like that might have become arrested thereon, anything arrested and then released by the plate 83 being discharged downwardly to the front of the coin-box 38 and finding its way to the discharge opening.

The sides 85 of the main frame 79 for the operative mechanism are connected at their lower front portions by the transverse bar or plate 86, hereinbefore referred to, at substantially their middle portions by the coin guide and positioning transverse plate 23, which is stationary, at their upper rear portions by a transverse rod 101 which serves to strengthen the frame and acts as a support for a series of depending shutter plates 182 hinged upon said rod, and at the lower rear portions the platform 104 with which the carriage 80 cooperates in its sliding movement to manipulate the coins fed to the machine for the purpose of ejecting the pieces of confection by the coin and the depositing of such coins in the coin receptacle.

An important feature of this invention resides in the improvement of the merchandise-ejecting mechanism by effectively excluding and clearing away from the parts cooperating

with the coin-carriage 80 all extraneous matter which might obstruct in the path of the said carriage 80 in its movement of the coin against the pieces of confection and also by effectively aiding in the guiding of the pieces of confection immediately after dislodgment thereof by the coins from the tray, and comprises the use of a hinged member movable with the carrier and extending into contact with and during movement of the carrier closely hugging the cooperating parts to exclude extraneous matter in the initial position of the carriage from the working parts of the carrier mechanism and during movement of the carriage to sweep and clear such cooperating parts and thereafter to assume a position which will effectively guide movement of the dislodged piece of merchandise and facilitate the discharge thereof.

Thus a platform 104, which is arranged below the tray and over which the coins are carried by the carriage, comprises at its front side an upwardly inclined section having a surface 106 up which coins are moved during the operation of the carrier, a central portion or section having coin slots 107 down through which the coins finally pass to the coin receptacle 38 and a rear portion 108 having a downwardly inclined portion for the purpose of guiding the swinging movement of a clearing and guiding member movable with the carrier, as hereinafter specified. Thus, a clearing and confection guiding member comprising a plate 127 is hinged by hooks 127' at one of its side edges on the rear edge of the carrier and in its initial operated position extends forwardly and has its other side edge engaging said coin-engaging upwardly inclined surface, thus excluding pieces of paper or other extraneous matter from the path of the coins and carrier operating mechanism, and the said hinging of the said plate member, enables it during movement of the carrier to closely hug the platform and to be guided thereby to move in a vertical plane upwardly over said inclined forward portion, thence horizontally over said central slotted portion for the deposit of the coins so as to clear the same of any extraneous matter, such as paper or the like which may rest thereon, and thereafter to swing downwardly over the downwardly inclined rear portion 108, all such movements being caused by the hinging of said plate at one edge on the carrier and the guiding contact of the other edge with said platform during the movement of the carrier.

It will be seen that the downwardly-inclined rear portion of the platform serves as a limiting stop for the downward movement of the combined guiding and clearing plate 127, its dropping movement being arrested by this downwardly inclined surface in position to engage and positively direct the discharge of the piece of confection

from the position at which it is released by the coin into the channel or chute 41.

When a coin is carried rearwardly over the platform 104, its lower edge rides up the inclined surface 106, and if the movement of the operating rod or handle 45 is continued outwardly without interruption, the coin will continue its movement rearwardly to the coin-slot 107 and be released to escape downwardly through said coin-slot.

The series of shutter plates 182 hinged on the rod 101 hang downwardly, as shown in Fig. 1, at the rear of the lower ends of the compartments of the tray 37 and protect the goods in said compartments from being interfered with by a wire which might be inserted upwardly along the chute 41. When the machine is in operation and in the act of ejecting a piece of confection, said piece will move against the shutter plate 182 in line with it and turn said shutter plate rearwardly, and after the descent of the ejected piece of confection, as indicated by the dotted lines in Fig. 2, said shutter plate will return to its normal hanging position shown in Fig. 1. The plates 182 are also advantageous in that the ejected pieces of confection are, at their rear ends, tilted downwardly by their engagement with said plates and caused to freely descend into the chute 41.

As one means for preventing the return movement of the carriage 80 before it has completed its full rearward movement, I provide the openings 95 which communicate with the coin slot 107 and receive the lower edges of the coins being transported so that in the event of pulling force being released on the rod or handle 45, said coins will engage the walls of said openings 95 and becoming arrested thereby, arrest the carriage 80 against forward movement. I thus utilize the coins transported by the carriage 80 to prevent the return movement of the carriage to its initial position before it has completed its full rearward movement. It may be mentioned that after the coins pass into vertical alignment with the front edges of the openings 95, the upper edges of the coins become engaged by the tray flanges 29, 69 and become depressed thereby so that the lower portions of the coins are compelled at their lower edges to enter the coin slots 107.

The carriage 80 of this invention may be of any suitable form by which coins will be carried against the pieces of confection for the purpose of ejecting them, and as illustrated is similar to that shown in my co-pending application Serial No. 82,662, filed January 21, 1926, and has a transverse bar 119 having a folded edge and cut out at said edge to form coin slots 126 which slots are in horizontal line with the final coin delivery slots 107 in the table or platform 104. The side members 122 of the carriage 80 con-

tains slots 128, and at the ends of the upper member 121 of the bar 119 are formed hooks 129.

Upon the carriage 80 is placed a coin-tester member 130, which is slidable upon the carriage 80, and to this end the side members 131 of the bar 130 are equipped with depending pins 134, which extend downwardly through the slots 128 in said members 122. The pins 134 and slots 128 are provided to permit the bar 130 to slide with the carriage 80 and also permit the carriage 80 to have a final rearward movement independently of the bar 130 so as to release the coins to descend through the slots 107. A coin conveyed to the machine may, after passing down the plate 83 and against the front face of the plate 23, enter one of the slots 126 of the carriage 80 and the corresponding recess of the coin-tester member 130, and rest upon two of the projections 132 of said bar 130, as I illustrate in Fig. 1 wherein 139 denotes a coin positioned for effecting the operation of the machine on the outward pull of the handle 45.

When the handle 45 is pulled outwardly with the coin 139 in position, the coin-plate 83 will swing frontwardly by gravity and the edges of the slot 126 of the carriage 80 and corresponding recess 137 of the bar 130, will force or move the coin, while on edge, rearwardly through a recess 22 in the plate 23 and through a recess 26 in the tray plate 27, and against the forward end of the lower piece of confection 61, the continued rearward movement of the coin resulting in the lower piece of confection being moved rearwardly against and opening the shutter 182, as shown in Fig. 2, and finally in said lower piece of confection passing entirely from the tray 37 and descending through the chute 41 to the opening at the lower front portion of the machine. During the rearward movement of the coin 139, the carriage 80 and coin-tester member 130 move together until the carriage has almost completed its rear stroke, and at that time the lower ends of the pins 135 reach the forward edge of the platform 104 and become arrested thereby, the arresting of the pins 134 preventing the coin-tester plate 130 from having any further rearward movement. At this time, however, the carriage 80 may and does move further rearwardly so that its slots 126 are carried beyond the projections 132 of the bar 130 and directly over the slots 107 in the table or platform 104, which is the condition shown in Fig. 2. The movement of the slots 126 of the carriage 80 beyond the projections 132 of the bar 130 and over the slots 107 results in the coins being released and permitted to descend through said slots 107. When the coins are in the slots 126 of the carriage 80 they are supported by the member 130, and hence when the slots 126

are carried rearwardly beyond said projections 132, the coins become unsupported and freely fall from the slots 126 and through the slots 107, passing to the cash box.

The slots 128 in the carriage members 122, 70 permit the carriage 80 to be moved a limited distance rearwardly independently of the coin-tester member 130 after said plate 130 has become arrested by the engagement of its pins 135 with the forward edge of the platform 104, and during this additional rearward movement of the carriage 80, the hooks 129 thereof pull against and increase the tension of the springs 136. On the return frontward movement of the carriage 80 under the action of the springs 84 and levers 81, the springs 136 draw the coin-tester plate 130 into the fold of the carriage-bar 119 or to its initial position as soon as the carriage has moved frontwardly the slight distance it previously moved rearwardly beyond the member 130 when said member 130 became arrested to relieve its support from the coins.

On the first positioning of the coin 139 90 in the slot 126 of the carriage 80 and in the corresponding recess 137 of the coin tester and support 130, the coin projects downwardly at the front of the platform 104 and in line with one of the upwardly extending inclined surfaces 106 thereof and thereafter as the carriage 80 and plate 130 are moved rearwardly, the coin rides up the said inclined surface 106, as hereinbefore described, and rearwardly across the platform 104. The elevation of the coin by riding up the surface 106 carries the coin upwardly from the projections 132 bordering the recess 137 in which the coin was initially positioned, and this freedom of the coin in respect to the plate 130 permits the flanges 29, 69 at the bottom of the tray 37 to force the coin downwardly against the top surface of the platform 104 and to compel the coin to pass downwardly, during its rearward movement, into and along an opening 95 of said platform and to the slot 107.

In order to facilitate the turning downwardly of the rear end of an ejected piece of confection, as shown in Fig. 2, I make 115 the goods supporting flanges 29, 69 of the tray 27 of reduced length, said flanges not being permitted to extend to the rearward edge of the tray and in length being about two-thirds of the depth of the tray, thus leaving rear end portions of the pieces of confection unsupported. When the flanges 29, 69 are thus shortened, the rear end of the pieces of confection being ejected have a tendency to turn downwardly, and the shutter 182 aids in the tendency of the piece of confection to turn downwardly and prevents said piece from turning upwardly.

The hinged plate 127 carried at the rear edge of the carriage 80 when it assumes an 130

inclined position positively guides the discharging movement of the piece of confection by engagement with the lower portion thereof and directs said piece of confection 5 into vertical position for discharge through the chute 41, the piece of confection after starting downwardly sliding over the face of said plate 127 in its inclined position and being prevented from taking any position 10 except one which is substantially vertical and leading into the chute 41 and beyond any part of the mechanism which might tend to affect the descent of the piece of confection.

15 Should for any reason a piece of confection become lodged on the platform 104 during a previous operation of the machine, said piece on the succeeding operation of the machine would be moved rearwardly by 20 the plate 127 and carriage 80 and be ejected at about the same time that the bottom piece 61 in the tray is at such operation discharged.

25 The operation of the several parts of the machine has hereinbefore been described in detail in connection with the description of the construction and arrangement of said parts. The pieces of confection 61 will be placed in the tray 37 endwise so that the 30 ends of said pieces may project forwardly and rearwardly, respectively.

The coins entered through the slots 59 pass to position at the foot of the respective compartments from which the goods 35 are to be sold, and when a coin has been entered through any slot 59, it will slide down the plate 83 to position, the coin entering one of the slots 126 of the carriage 80 and the corresponding portion of the coin-tester member 130 as shown in Fig. 1. 40 The coin being thus in position, the handle 45 is pulled outwardly to cause the carriage 80 and bar 130 to move rearwardly and carry the coin against the lower piece of confection of a stack thereof for ejecting said 45 piece to descend through the chute 41 to the purchaser. During the outward movement of the handle 45 and rearward movement of the carriage 80 and bar 130 with the coin positioned to act as a goods ejector, said carriage and coin-tester member move together until the carriage is approaching the end of its stroke, and at that time the coin-tester member 130 becomes arrested by the 50 engagement of the pins 134 with the platform 104 and the carriage moves on to a limited extent without said member, with the result that the coin is carried rearwardly beyond the member 130 and over a slot 107, 55 through which the coin, then unsupported, will descend to the coin-box. The parts will then return to their normal position under the action of the springs 84 and levers 81, the initial relation of the carriage 80

and coin-tester member 130 being restored 65 by the springs 136.

Having described my invention, I claim:

1. A coin-controlled vending machine embodying, in combination, a vertical tray partially open at its lower end for supporting columns of pieces of merchandise to permit edgewise ejection of the pieces successively, an exposed manually-operable handle, a horizontally-slidable carriage operable from 70 said handle and having vertical coin slots therein apportioned to said columns, means on said carriage for supporting coins to stand on edge in said slots in position to successively engage and dislodge the lower 75 pieces in said columns when the carriage is operated by said handle, a platform arranged below the tray over which the coins are carried by said carriage, comprising a 80 coin-lifting section having an upwardly inclined surface arranged to engage and lift the coins during the movement thereof by the carriage, a horizontal centrally-disposed coin-depositing section having slots through 85 which the coins descend when released by the carriage and a member movable in a vertical plane carried by the carrier and engaging the inclined surfaces of said coin-lifting section to cause a movement of said member vertically upwardly over said upwardly inclined forward platform portion and horizontally over said central portion, such movements being caused by engagement of said member with said platform during the movement by the carrier, where- 90 by the space between the carriage and said coin-lifting inclined surface will be closed against admission of extraneous matter and any such matter falling on the platform 95 will be carried by the movement of the carrier to the rear of the machine.

2. A coin-controlled vending machine embodying, in combination, a vertical tray partially open at its lower end for supporting columns of pieces of merchandise to permit edgewise ejection of the pieces successively, an exposed manually-operable handle, a horizontally-slidable carriage operable from 100 said handle and having vertical coin slots therein apportioned to said columns, means on said carriage for supporting coins to stand on edge in said slots in position to successively engage and dislodge the lower 105 pieces in said columns when the carriage is operated by said handle, a platform arranged below the tray over which the coins are carried by said carriage, comprising a coin-lifting section having an upwardly inclined surface arranged to engage and lift the coins during the movement thereof by 110 the carriage, a horizontal centrally-disposed coin-depositing section having slots through 115 which the coins descend when released by the carriage, a horizontal centrally-disposed coin-depositing section having slots through 120 which the coins descend when released by 125

the carriage, and a plate hinged at one side edge on the carrier and having its other side edge engaging the inclined surface of said coin-lifting section to cause a movement of said plate vertically upwardly over said upwardly inclined forward platform portion and horizontally over said central portion, such movements being caused by engagement of said plate with said platform during the movement by the carrier, whereby the space between the carriage and said coin-lifting inclined surface will be closed against admission of extraneous matter and any such matter falling on the platform will be carried by the movement of the carrier to the rear of the machine.

3. A coin-controlled vending machine embodying, in combination, a vertical tray partially open at its lower end for supporting columns of pieces of merchandise to permit edgewise ejection of the pieces successively, an exposed manually-operable handle, a horizontally-slidable carriage operable from said handle and having vertical coin slots therein apportioned to said columns, means on said carriage for supporting coins to stand on edge in said slots in position to successively engage and dislodge the lower pieces in said columns when the carriage is operated by said handle, a platform arranged below the tray over which the coins are carried by said carriage, comprising a coin-lifting section having an upwardly inclined surface arranged to engage and lift the coins during the movement thereof by the carriage, a horizontal centrally-disposed coin-depositing section having slots through which the coins descend when released by the carriage, and a rear portion extending downwardly and rearwardly to form a downwardly inclined support, and a member movable in a vertical plane carried by the carrier and engaging the inclined surface of said coin-lifting section to cause a movement of said member vertically upwardly over said upwardly inclined forward platform portion, horizontally over said central portion, and downwardly over said downwardly and rearwardly inclined portion, all such movements being caused by engagement of said member with said platform during the movement by the carrier, whereby the space between the carriage and said coin-lifting inclined surface will be closed against admission of extraneous matter and any such matter falling on the platform will be carried by the movement of the carrier to the rear of the machine and

through the discharge opening and the inclination of said member lying flat against the rearwardly inclined portion of said platform will serve as a downwardly inclined guide for the discharge of a piece of merchandise.

4. A coin-controlled vending machine embodying, in combination, a vertical tray partially open at its lower end for supporting columns of pieces of merchandise to permit edgewise ejection of the pieces successively, an exposed manually-operable handle, a horizontally-slidable carriage operable from said handle and having vertical coin slots therein apportioned to said columns, means on said carriage for supporting coins to stand on edge in said slots in position to successively engage and dislodge the lower pieces in said columns when the carriage is operated by said handle, a platform arranged below the tray over which the coins are carried by said carriage, comprising a coin-lifting section having an upwardly inclined surface arranged to engage and lift the coins during the movement thereof by the carriage, a horizontal centrally-disposed coin-depositing section having slots through which the coins descend when released by the carriage, and a rear portion extending downwardly and rearwardly to form a downwardly inclined support and a plate hinged at one side edge on the carrier and having its other side edge engaging the inclined surface of said coin-lifting section to cause a movement of said plate vertically upwardly over said upwardly inclined forward platform portion, horizontally over said central portion, and downwardly over said downwardly and rearwardly inclined portion, all such movements being caused by engagement of said plate with said platform during the movement by the carrier, whereby the space between the carriage and said coin-lifting inclined surface will be closed against admission of extraneous matter and any such matter falling on the platform will be carried by the movement of the carrier to the rear of the machine and through the discharge opening and the inclination of said hinged plate lying flat against the rearwardly inclined portion of said platform will serve as a downwardly inclined guide for the discharge of a piece of merchandise.

In witness whereof, I have signed my name to the foregoing specification.

HARVEY GILES.
